Inventor,
Charles L. McCuen
By Rector, Hobson, Davis & Macaulay,
Inc. Attn.

UNITED STATES PATENT OFFICE.

CHARLES L. MCCUEN, OF CHICAGO, ILLINOIS, ASSIGNOR, BY MESNE ASSIGNMENTS, TO
DELCO-LIGHT COMPANY, OF DAYTON, OHIO, A CORPORATION OF DELAWARE.

REFRIGERATING APPARATUS.

Application filed January 17, 1920. Serial No. 352,040.

To all whom it may concern:

Be it known that I, CHARLES L. MCCUEN, a citizen of the United States, residing at Chicago, in the county of Cook and State 6 of Illinois, have invented certain new and useful Improvements in Refrigerating Apparatus, of which the following is a specification.

My invention relates to refrigerating apparatus of the type in which a compressible refrigerant such as sulfur dioxid is employed and the object thereof is to produce a simple, efficient and compact apparatus of this type.

15 In the drawings Fig. 1 is a sectional elevation of an apparatus embodying my invention. Fig. 2 is a section on the line 2—2 of Fig. 1 and Fig. 3 a view showing an end elevation of the combined pump and 20 condenser chamber and a vertical section of the expansion coils and the brine tank.

Referring to the particular embodiments of my invention as shown in the drawings the same comprises a single cylinder 1, a 25 chamber 2 which is a combined pump chamber and condenser chamber containing the pump 3 and the condenser coils 4 as well as cooling coils 5 for the body of oil in which in practice the pump is submerged. 30 This pump is driven by a prime mover such as an electric motor 6 and such motor and cylinder or tank 1 are preferably mounted upon a single base plate 7. Preferably secured to this plate and depending therefrom 35 is a brine tank 8 within which are arranged the refrigerating coils 9 which communicate with the chamber through a suitable expansion valve 10.

Describing the several parts in detail the 40 pump 3 is of the same general construction and operation as that described in Leonard Patent 1,235,069 dated July 10th, 1917 and the same is driven by the motor 6 through the horizontal shaft 11. It will be understood that the chamber 2 is provided with 45 a body of oil up to a predetermined level somewhere between the level test cocks 2' below which is the body of liquid refrigerant, and that the pump 3 and the cooling coils 5 are located in substantially the 50 same zone and are submerged in the body of oil. The pump discharges the gas through the pipe 12 against the bottom of the plate 13 which acts as a baffle plate 55 as well as a drip pan.

The condenser coils 4 are located in the upper portion of the chamber 2 in the space occupied by the refrigerant gas under compression after being discharged from the pump. These coils are supported above and partly within the shallow tank or drip pan 13, which is supported from the base of the tank 1 in suitable manner as by means of the vertical rods 14 and the pipe connections hereinafter described. These coils 4 60 form part of a water circulating system, the water entering such coils through the vertical pipe 15 and after passing through the condenser coils it enters the inlet end 16 of the cooling coils 5 which are intended to maintain the body of oil at the proper temperature. The water then flows through the coils 5 and passes outwardly from the tank 1 through the passage 17 which is controlled by the valve 18. The connection between the outlet of the condenser coils and the inlet 16 of the coils 5 is through the bottom of the drip pan 13 as indicated at 19. The coils 5 are suitably supported upon the base of the tank 1 as 65 by means of the vertical rod 20 and the baffle 21 which is itself supported on the rod 20 by the tube 22.

After the refrigerant gas is condensed by the coils 4 it drops as a liquid into the pan 13 and is then conducted downwardly through the vertical pipe 23 which is screw threaded into the bottom opening 24 of such pan. This pipe 23 surrounds the water pipe 15 and extends downwardly to near the 70 bottom of the tank so as to discharge the liquid refrigerant below the body of oil which is of less specific gravity than the 75 condensed refrigerant. By preference the bottom of the tank 1 is provided with a 80 central depression forming a well 25 into which extends the take-off pipe 26 which leads to the expansion valve 10, entering the casing of the latter through the pipe 27, Fig. 3.

The expansion valve may be of any well known construction and as shown the controlling valve 28 thereof controls the passage of the refrigerant through the passage 29 to the inlet end 30 of the refrigerating or expansion coils 9. The outlet end 31 of these coils extends upwardly and is connected by the pipe 32, fittings 33 and pipe 34 with the suction of the pump.

It will be understood that the refrigerat- 110

ing coils may be directly inserted into the cooling chamber or other chamber of the refrigerator but in the present instance I have shown the same as contained within a suitable brine tank 8 which is fastened at its upper end to a horizontal head block 35 which is in turn secured by means of bolts 36 to the underside of the base plate 7. The coils 9 are held supported within the brine tank in suitable manner as by means of the straps 37 secured to the block 35. These coils are also held in position by vertical straps 38. In order to carry away any drip from the top of the base plate 7 adjacent the expansion valve, I provide a vertical drip pipe 39 which extends into a vertical pipe 40 passing through the brine tank with the result that the drip is conducted to a point below such tank.

20 In this manner and by these means I produce a refrigerating apparatus provided with a single tank having all of the functions of the double tank or cylinder type and provide a single cylinder construction 25 very compact and of comparatively small compass considering the capacity thereof.

I claim:

1. In a refrigerating apparatus the combination of a combined pump chamber and condenser chamber, a pump therein, condenser coils located at the upper portion of the chamber, cooling coils located at an intermediate portion thereof and substantially at the same level as the pump, an expansion valve communicating with the bottom of the chamber, and refrigerating coils communicating with the expansion valve and with the pump.

2. In a refrigerating apparatus the combination of a combined pump chamber and condenser chamber, a pump therein, condenser coils located at the upper portion of the chamber, cooling coils located at an intermediate portion thereof and substantially 45 at the same level as the pump, a drip pan arranged below the condenser coils and having an outlet communicating with the chamber near its bottom, an expansion valve communicating with the bottom of the chamber, and refrigerating coils communicating with the expansion valve and with the pump.

3. In a refrigerating apparatus the combination of a combined pump chamber and condenser chamber, a pump therein, condenser coils located at the upper portion of the chamber, cooling coils located at an intermediate portion thereof and substantially at the same level as the pump, a drip pan which is arranged below and supports the condenser coils such pan having a bottom outlet for the refrigerant, a pipe communicating with such outlet and extending to near the bottom of the chamber, an expansion valve communicating with the bottom 60 of the chamber, and refrigerating coils com-

municating with the expansion valve and with the pump, the inlet pipe of the condenser coil passing upwardly through the refrigerant pipe and connected with the condenser coils.

70

4. In a refrigerating apparatus, in combination, a tank having a chamber, a condensing coil mounted in said chamber having a vertically extending supply pipe, a drip pan for the condensed refrigerant below the coil, and an outlet pipe from the drip pan surrounding a part of said supply pipe.

75

5. In a refrigerating apparatus, the combination of a pump chamber, a pump in said chamber, the chamber containing a body of oil in the zone of the pump, cooling coils also located in said body of oil, condenser means, means for conducting the liquid refrigerant as condensed by the condenser means to the bottom of said chamber and under the oil, an expansion valve communicating with the bottom of the chamber, and refrigerating coils communicating with the expansion valve and with the pump.

80

6. In a refrigerating apparatus, the combination of a pump, a chamber containing a body of oil, condenser means, a pipe extending through said body of oil for conducting the liquid refrigerant as condensed by the condenser means to the bottom of the chamber and under the oil, an expansion valve communicating with the bottom of the chamber, and a refrigerating coil communicating with the expansion valve and with the pump.

85

7. In a refrigerating apparatus, a tank having a pump chamber, a pump mounted in said chamber and adapted to discharge refrigerant therein, means at the upper portion of said chamber for condensing said refrigerant, a drip pan in said chamber intermediate the condensing means and the pump for receiving the condensed refrigerant, and an expansion coil communicating with said pump and said chamber.

90

8. In a refrigerating apparatus, a tank having a pump chamber, a pump mounted in said chamber and adapted to discharge refrigerant therein, said pump having an upwardly extending outlet opening, means at the upper portion of said chamber for condensing said refrigerant, a drip pan in said chamber intermediate the condensing means and the pump for receiving the condensed refrigerant and for forming a baffle for the gas from the pump outlet, and refrigerating coils communicating with said pump and said chamber.

95

9. In a refrigerating apparatus, in combination, a housing, a compressor in said housing, a refrigerating coil outside the housing and operatively connected with the compressor, and condensing means inside said housing, said condensing means includ-

100

105

110

115

120

125

ing a condenser coil, a vertically disposed refrigerant pipe within the housing, and a condensing-water pipe concentric with the refrigerant pipe and arranged to cool the refrigerant therein.

10. In a refrigerating apparatus, in combination, a housing, a compressor in said housing, a refrigerating coil outside the housing and operatively connected with the compressor, and condensing means inside said housing, said condensing means including a condenser coil, a vertically disposed refrigerant pipe within the housing, and a condensing-water pipe concentric with the refrigerant pipe and arranged to cool the refrigerant therein, said housing having a water passage extending horizontally through the bottom wall and opening upwardly into the interior of the housing, and means for rigidly securing said water pipe to the bottom wall of the housing in communication with the water passage.

11. A refrigerating unit adapted to be

applied to a refrigerating box, and comprising a base, a compressor, motor and condenser mounted upon the base, a refrigerating coil suspended from the base within the refrigerator, means for connecting said compressor, condenser and refrigerating coil in a refrigerating circuit, and a drain passage extending through said base from the exterior of said refrigerator to the interior thereof.

12. In a refrigerating apparatus, in combination with a refrigerating box, a refrigerating circuit including a compressor, condenser and expansion valve outside of the box, a refrigerating coil inside said box and having a portion thereof extending through the wall of said box, said expansion valve being connected to the extended portion of said refrigerating coil, and a drain passage extending through the wall of the refrigerator adjacent to said extended portion.

CHARLES L. McCUEN.
